UNITED STATES PATENT OFFICE.

CHARLEY W. ANDERSON, OF PORTAL, NORTH DAKOTA, ASSIGNOR OF ONE-HALF TO THEODORE THORESON, OF PORTAL, NORTH DAKOTA.

GRAIN-SHOCKING MACHINE.

No. 846,888.

Specification of Letters Patent. Patented March 12, 1907.

Application filed November 12, 1906. Serial No. 343,087.

To all whom it may concern:

Be it known that I, CHARLEY W. ANDERSON, a citizen of the United States, residing at Portal, in the county of Ward and State of North Dakota, have invented a new and useful Grain-Shocking Machine, of which the following is a specification.

This invention relates to grain-shocking machines.

The objects of the invention are to improve and simplify the construction of such machines; furthermore, to increase their efficiency in operation and to decrease the expense attending their manufacture.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of the following claims without departing from the spirit of the invention or sacrificing any of its advantages.

In the accompanying drawings, forming part of this specification, Figure 1 is a side elevation of a shocking-machine constructed in accordance with the invention looking at the side thereof which is disposed toward the binder. Fig. 2 is a front elevation of the improved machine. Fig. 3 is an under plan view of the machine. Fig. 4 is a vertical section, partly in elevation, through the shocking-chamber and the means for raising the rotary shocking member. Figs. 5, 6, 7, 8, 9, and 10 are detail views.

Like reference-numerals indicate corresponding parts in the different figures of the drawings.

The shocking-machine of the present invention is constructed with any suitable form of framework or platform A, which is supported by means of a large ground-wheel 1 and a small carrying-wheel 2. The platform A of the machine along one side thereof is secured to a binding-machine in any suitable manner, such as by means of the brackets 3. (Shown in Fig. 2.) The ground-wheel 1 is journaled in a rectangular frame 4, which is mounted for vertical sliding movement in a slightly larger rectangular frame 5, the lower ends of which are provided with flanges 6, bolted or otherwise suitably secured

to the platform A. The stationary frame 5 has formed in its sides vertical slots 7, as shown in Fig. 1, to receive bolts 8, which are secured to the slideable frame 4 in any suitable manner. For the purpose of permitting yielding upward movement of the frame 4 and ground-wheel 1 with respect to the frame 5 a coil-spring 9 is interposed between the upper end of the frame 4 and the frame 5. Rigidly secured to the upper end of the slideable frame 4 and extending loosely upward through the frame 5 is a bolt 10, which passes through the center of the coil-spring 9 and is provided at its upper end with an adjusting-nut 11. By tightening the nut 11 the frame 4 will be drawn positively upward in the frame 5, and said bolt 10 will limit the downward movement of the frame 4 without preventing the coil-spring 9 from permitting an upward yielding movement thereof whenever the wheel 1 strikes an obstruction. It will be obvious, therefore, that by tightening the nut 11 the platform A can be drawn downward closer to the ground whenever desired.

The conveying means for receiving a sheaf of grain from the binder and carrying the same into the shocking-chamber, to be hereinafter described, preferably consists of a pair of endless aprons or belts 12 13, which are slightly inclined from the vertical, as shown in Fig. 1, and are adapted to form between them a channel 14, along which the sheaf of grain is carried, it being understood that the sheaf is fed from the binder in such manner that it will enter the channel 14 in an approximately vertical position with the heads of the grain upward. The means for operating the endless aprons 12 and 13 so that their inner portions will travel in the same direction preferably consists of a sprocket-chain 15, which is suitably connected with the vertical shafts of the belts 12 and 13. The sprocket-chain 15 is operated by means of a shaft 16, journaled in a bracket 17 upon the platform A. (See Fig. 1.) The shaft 16 is provided with a bevel-gear 18, which is operated by means of a bevel-gear 19, said bevel-gear 19 in turn being rotated by a sprocket-chain 20. The sprocket-chain 20 is engaged with a suitable sprocket-wheel upon a main shaft 21, which is rotated by means of a sprocket-chain 22, connected at its lower end with a sprocket-wheel upon an intermediate shaft 23, journaled in brackets

or uprights 24 upon the platform A. The intermediate shaft 23 is rotated by means of a sprocket-chain 25, connected with a sprocket-wheel 26, which is carried by the ground-wheel 1. The conveying means, consisting of the endless belts 12 and 13, serves to carry each sheaf of grain through a door 27, formed in one side of a frusto-conical shocking-chamber 28, which is mounted upon the platform A, as illustrated in Fig. 4.

Mounted in the shocking-chamber 28 is a rotary member B, comprising a vertical shaft 29, to the lower end of which is secured a plurality of radial blades 30, said blades being preferably connected with the shaft 29 by means of spring brackets or arms 31. In the embodiment of invention illustrated four radial blades 30 are employed, so as to divide the shocking-chamber 28 into four sections or compartments, although it is to be understood that a greater or lesser number of blades 30 can be employed. Each of the compartments formed by the radial blades 30 in the shocking-chamber 28 in the present instance is intended to hold three sheaves of grain, so that a shock when formed will contain twelve sheaves of grain. As each compartment formed by the blades 30 will hold only three sheaves of grain, it will be apparent that the rotary member, consisting of said radial blades, must be rotated one step each time three sheaves of grain have been fed to the shocking-chamber, so that an empty compartment will be disposed opposite the door 27.

The means for operating the rotary member in the shocking-chamber 28 each time three sheaves of grain have been fed to said chamber preferably comprises the following mechanism: Journalized in bearing-plates 32 upon stationary supporting members 33 at the upper ends of the endless belts 12 and 13, as shown in Figs. 1 and 2, is a rock-shaft 34, which is provided with a rigid depending arm 35, the lower end of which is broadened, as shown at 36, and is located in the channel 14 between the endless belts 12 and 13, so that each time a sheaf passes along the channel 14 its upper end will engage the lower end of the rigid arm 35 and rock the shaft 34. Extending upward from the shaft 34 is a rigid arm 37, with the upper end of which is connected a flexible element 38, that extends upward and is connected with a lever 39, loosely fulcrummed upon a stud-shaft 40, which is suitably journaled in a supporting-frame 41. The lever 39 at its free end is normally drawn upward into raised position by means of a coil-spring 42. It will be understood that each time a sheaf of grain moves through the channel 14 and operates the arm 35 the lever 39 will be drawn downward against the tension of the spring 42, and after the sheaf has passed out of contact with the arm 35 the spring 42 serves to re-

store said arm to proper position to be engaged by the next sheaf.

Rigidly mounted upon the stud-shaft 40 is a disk 43, having three ratchet-teeth or cam members 44, which are so arranged that each time the lever 39 is moved downward by a sheaf of grain it will engage one of the cam members 44 and will rotate the disk 43, and consequently the shaft 40, one step, after which the spring 42 will draw the lever 39

upward into position to engage the next cam member, it being understood that the loose mounting of said lever upon the stud-shaft 40 permits it to ride upward over the inclined faces of the cam members 44 and 80 that the spring 42 draws it in behind each cam member, so as to engage the same on its downward movement. Rigidly connected with the stud-shaft 40 on the side of the supporting-frame 41 opposite the disk 43 is a ratchet-wheel 45, with which cooperates a pawl 46, mounted upon the supporting-frame 41. The ratchet-wheel 45 is provided with an eccentrically-mounted pin 47, which during each rotation of the ratchet-wheel 45 90 is adapted to engage and rock a lever 48, fulcrumed at its upper end 49 loosely upon a shaft 50, which is journaled in the supporting-frame 41, as shown. The lever 48 is drawn normally to the right in Fig. 1 by means of a coil-spring 51, so that it will be held yieldingly in contact with the eccentric-pin 47 on the ratchet-wheel 45. At its lower end the lever 48 is connected with a link 52, which is suitably secured to a bell-crank lever 53, fulcrumed upon a bracket 54. The bell-crank lever 53 is bifurcated, as indicated at 55 in Fig. 2, and is engaged by a clutch member 56, splined upon the main shaft 21. Loosely mounted upon the main shaft 21, adjacent the slidable clutch 56, is a clutch 57. When the lever 48 is operated by the eccentric-pin 47 on the ratchet 45, the bell-crank lever 53 is rocked, so as to throw the splined clutch member 56 into engagement with the loose clutch member 57, and thus cause said member 57 to rotate with the main shaft 21. Secured upon the loose clutch member 57 is an eccentric disk 58, which when the clutch member 57 is rotated by the shaft 21 is 115 adapted to contact with and rock to the left in Fig. 1 a lever 59, which is journaled at its lower end 60 upon a fulcrum-plate 61 upon the platform A.

The lever 59 at its upper end is connected with a link-rod 62, having on the rear end thereof a hook portion 63, which is adapted to engage one of the teeth of a ratchet-wheel 64, mounted rigidly upon the shaft 29 of the rotary member B. It will be obvious that when the splined clutch member 56 is thrown into engagement with the loose clutch member 57 and the eccentric 58 is rotated to rock the lever 59 the link 62 will be drawn to the left in Fig. 1 and the hook 63 will engage one 130

of the teeth of the ratchet-wheel 64, so as to move the rotary member B one step, and thus bring an empty compartment into position opposite the door 27. By reason of the fact that the disk 43 has three cam members it will be apparent that each time three sheaves of grain have passed through the channel 14 the disk 43 will have been caused to make one complete revolution, so as to throw the clutch member 56 into gear, and thus move the rotary member B, as described. For the purpose of moving the link-rod 62 to the right in Fig. 1 after it has operated the rotary member B, so that the portion 63 of said link-rod will be in position to engage the next tooth of the ratchet-wheel 64, the lower end of the lever 59 is formed with an upwardly-extending crank portion 65, which fits over a flat spring 66, as shown in Figs. 1 and 2. The upward pressure of the spring 66 on the crank portion 65 of the lever 59 throws said lever 59, and consequently the link-rod 62, to the right in Fig. 1 as soon as a sheaf of grain by rocking the arm 35 in the channel 14 has stopped the further rotation of the member B by moving the eccentric-pin 47 away from the lever 48, and thus permitting the spring 51 to pull said lever 48 to the right in Fig. 1, whereby the bell-crank lever 53 is caused to disengage the clutch member 56 from the clutch member 57.

As previously intimated, each time twelve sheaves of grain have passed through the channel 14 between the conveyers 12 and 13 the rotary member B will have been given four movements and will have made one complete revolution, so that the shocking-chamber 28 will be filled with twelve sheaves of grain. At this time it is desired that the rotary member B shall be moved bodily upward within the shocking-chamber and that simultaneously a rearwardly and upwardly swinging door connected with the shocking-chamber and a pair of sliding doors forming the bottom of said shocking-chamber shall be opened, so that the shock, consisting of the twelve sheaves of grain, shall be permitted to drop downward out of the shocking-chamber 28 and to be left in proper position upon the ground.

The means for moving the rotary member B upward when the shocking-chamber 28 is filled will now be described. Splined upon the shaft 29 of the rotary member B is a gear-wheel 67, which is in mesh with a similar gear-wheel 68, journaled upon a bracket 69, which is supported upon a cross-piece 70, held in proper position upon the supporting-frame 41 by means of adjustable collars 71. It will be understood that each time the rotary member B has made one complete revolution each of the gear-wheels 67 and 68 will also have made one complete revolution. The gear-wheel 68 on its upper surface is provided at one point with a projection 72,

which is adapted once in every revolution of said gear-wheel 68 to wipe under and rock a lever 73, fulcrumed at 74 upon a supporting-arm 75, connected with the frame 41. At its upper end the lever 73 is pivotally connected with a smaller lever 76, fulcrumed at 77 upon the supporting-frame 41 and connected at its upper end with a clutch member 78, which is splined upon the shaft 50. Loosely mounted upon the shaft 50 is a clutch member 79, which is rotated in a continuous manner by means of a sprocket-chain 80 in gear with the main shaft 21, which, as before explained, is continuously rotated from the ground-wheel 1. Each time the rotary member B and consequently the gear-wheels 67 and 68 make one complete revolution, so as to rock the lever 73, the splined clutch member 78 is thrown into engagement with the loose clutch member 79, so that the shaft 50 is caused to be rotated by the clutch member 79. Mounted rigidly upon the shaft 50 is a large cam 81, which, as shown in Fig. 4, is disposed between a pair of idle wheels 82, journaled on stud-shafts 83 within a vertically-movable yoke 84, which is slotted at 85 for the passage of the shaft 50. The yoke 84 has a swivel connection at 86 with the shaft 29 of the rotary member B. It will be apparent that at the end of each complete revolution of the rotary member B when the clutch member 78 is thrown into engagement with the clutch member 79, as described, and the shaft 50 is rotated the cam 81 will raise the yoke 84, which in turn will raise the rotary member B, so as to draw the blades 30 upward out of engagement with the shock in the shocking-chamber 28.

At the moment that the rotary member B is raised in the manner described it is proposed to open the sliding doors, which form the bottom of the shocking-chamber 28, and also to open the swinging door, which forms the rear end of said shocking-chamber, so that the shock can drop to the ground and the machine can move forward, so as to leave the shock in proper position.

The construction and arrangement of the rear and bottom doors of the shocking-chamber 28 and the means for opening said doors when the rotary member B is raised will now be described. The reference-numeral 87 indicates a swinging door, which is pivotally mounted at 88 upon the rear end of the shocking-chamber 28. The door 87 is provided at its lower end with a heavy counter-weight 89 and at its upper end with a rigid upwardly-extending arm 90. Secured to the arm 90 is a flexible element 91, which is wrapped around a drum 92 fastened upon an auxiliary shaft 93, which is journaled in uprights 94 upon the platform A. The auxiliary shaft 93, as shown in Fig. 2, at the end thereof opposite the drum 92 is provided with a second rigid drum 95, around which is

wrapped a flexible element 96, which, as shown in Fig. 3, extends downward through an opening 97 in the platform A and is divided into two strands 98 and 99, one of which is connected with an arm 100 of a sliding door 101 and the other of which is connected with an arm 102 of a sliding door 103. The doors 101 and 103 are adapted to slide back and forth in guideways 104, so as to open and close the lower end of the shocking-chamber 28. Connected with each of the sliding doors 101 and 103 and with each of the arms 100 and 102 is a pair of coil-springs 105, the tendency of which is to draw the doors 101 and 103 into opened position and away from each other. The weight 89 upon the swinging door 87 of the shocking-chamber 28 is sufficiently heavy to swing said door 87 into closed position, thus drawing upon the flexible element 96 and unwinding the same from the drum 92. As the flexible element 96 is unwound from the drum 92 by the weight 89 the flexible element 96 is wound upon the drum 95, thus drawing the sliding doors 101 and 103 into closed position against the tension of the springs 105. It will be understood, therefore, that the weight 89 serves not only automatically to hold the swinging door 87 in closed position, but also the sliding doors 101 and 103.

For the purpose of opening the swinging door 87 and the sliding doors 101 and 103 when the rotary member B is raised the following mechanism is employed: Rigidly secured at 106 to the yoke 84, as shown in Figs. 1 and 2, is a depending arm 107, which, as shown in Fig. 5, is provided at its lower end with a latch 108, fulcrumed at 109 and having a rearwardly-extending arm 110 and a slot 111, through which extends a limiting-pin 112, mounted on the arm 107. As the arm 107 moves upward with the yoke 84 the face 113 of the latch 108 engages and rocks a lever 114, which is fulcrumed at 115 upon a supporting-arm 116, secured at 117 to the cross-piece 70 of the frame. As the lever 114 is rocked upward at its rear end by the latch 108 the forward end of said lever pushes downward upon a link-rod 118, which is pivotally connected with the lever 114, as shown at 119. Secured to the lower end of the link-rod 118, as shown in Fig. 2, is a bifurcated wedge member 120, which straddles the shaft 93 between a fixed collar 121 and a clutch member 122, which is splined on said shaft 93. As the wedge member 120 is forced downward by the rod 118 it pushes the clutch member 122 into engagement with a clutch member 123, which is loosely mounted on the shaft 93 and is continuously rotated by means of a sprocket-chain 124 from the continuously-rotated main shaft 21. It will be obvious, therefore, that as the yoke 84 is raised in the manner described to elevate the rotary member B the wedge 120 is moved

downward, so as to throw the clutch 122 into engagement with the clutch 123, whereby the shaft 93 is rotated in such manner as to wind the flexible element 96 upon the drum 92, so as to open the rear door 87 and at the same time to pay off the flexible element 96 from the drum 95, so as to permit the springs 105 to exert their influence to open the sliding doors 101 and 103. As the operations of raising the rotary member B and opening the swinging door 87 and the sliding doors 101 and 103 take place simultaneously, it will be obvious that the shock, consisting of the twelve sheaves in the shocking-chamber 28, will be dropped to the ground when the sliding doors at the bottom of said chamber are entirely opened and that the swinging door 87 by reason of the fact that it has been raised into opened position will clear the upper end of the shock. When the yoke 84 has reached its highest position, the arm 110 of the latch 108 comes into contact with a rigid stop member 125, which is secured to the machine-frame in any suitable manner and is formed with a bent end 126. The engagement of the arm 110 with the bent portion 126 of the stop member 125 serves to trip the latch 108 out of engagement with the lever 114. Said lever 114 is then immediately drawn downward into its lowermost position by a weight 127, which is secured to said lever, as shown in Fig. 1. The downward movement of the lever 114 draws the wedge 120 upward, so as to release the clutch member 122 from the clutch member 123, thus stopping the rotation of the shaft 93 while the door 87 is in raised position and the doors 101 and 103 are in opened position. The weight 89 on the door 87 then causes said door to move downward to closed position, thus rotating the shaft 93 through the flexible element 96 and causing the flexible element 96 to draw the sliding doors 101 and 103 into closed position against the action of the springs 105.

As previously explained, it is proposed that the lever 73 in Fig. 2 shall be employed for throwing the shaft 50 into operation to raise and lower the rotary member B when the shocking-chamber 28 contains twelve sheaves of grain. It may be here explained that the gear-wheel 68 makes a quarter-revolution each time three sheaves of grain have been fed to the shocking-chamber. After the last three sheaves have been fed to the shocking-chamber the gear-wheel 68 makes the last quarter of its revolution and during this last movement the projection 72 first rocks the lever 73, so as to throw the clutches 78 and 79 into engagement with each other and hold the same in said engagement until the shaft 50 has made one complete revolution, thereby raising and lowering the rotary member B. The projection 72 then slips from under the lever 73 and a spring 128

rocks said lever, so as to move the clutches 78 and 79 out of engagement with each other. It will be understood, therefore, that the rotation of the clutch member 79 must be sufficiently rapid to give the shaft 50 one complete revolution during the limited time that the projection 72 holds the clutches 78 and 79 in engagement with each other before slipping from under the lower end of the lever 73 at the end of the last quarter-revolution of the gear-wheel 68.

The reference-numeral 129 in Fig. 3 indicates a portion of a binder to which the brackets 3 are secured, and the reference-numeral 130 indicates a brace-rod which is secured to the outer forward corner of the shocking-machine and extends inward, so as to be connected with some suitable portion of the binder.

The improved shocking-machine of the present invention is strong, simple, durable, and inexpensive in construction as well as thoroughly efficient in operation. The rotary member B serves to hold the different sheaves in proper position in the shocking-chamber 28 to form a shock, and the frusto-conical shape of the shocking-chamber 28 serves to hold the upper end of the shock in contracted position. Furthermore, as the doors 101 and 103 are drawn apart to permit the shock to fall out of the shocking-chamber they serve to draw apart the lower ends of the shock, so as to give the same a broad base, and thus hold it in proper position upon the ground.

What is claimed is—

1. A shocking-machine having a shocking-chamber provided with bottom and rear doors, means for feeding sheaves to said shocking-chamber, and means for automatically opening said bottom and rear doors when said shocking-chamber becomes full.

2. A shocking-machine having a shocking-chamber provided with bottom and rear doors, a rotary member mounted in said shocking-chamber and dividing the same into a plurality of compartments, means for operating said rotary member each time one of said compartments becomes full, and means for automatically raising said rotary member and opening said bottom and rear doors when said shocking-chamber becomes full.

3. A shocking-machine having a shocking-chamber provided with doors, a rotary member mounted in said shocking-chamber and dividing the same into a plurality of compartments, conveying means for feeding sheaves to said shocking-chamber, and means operated by the passage of sheaves through said conveying means for operating said rotary member each time one of said compartments becomes full and for raising said rotary member and opening said doors when said shocking-chamber becomes full.

4. A shocking-machine having a shocking-chamber, a swinging rear door connected with said shocking-chamber and having a weight, a sliding bottom door having a connection with said swinging door and adapted to be closed thereby, means for feeding sheaves to said shocking-chamber, and means for automatically opening said doors when said shocking-chamber is full. 75

5. A shocking-machine having a shocking-chamber, a weighted rear door for said shocking-chamber, a bottom door for said shocking-chamber, a flexible connection between said weighted rear door and said bottom door, means for feeding sheaves to said shocking-chamber, and means for automatically opening said rear and bottom doors when said shocking-chamber is full. 80

6. A shocking-machine having a shocking-chamber, a rotary and vertically-movable member in said shocking-chamber, rear and bottom doors for said shocking-chamber, an operating connection between said rear and bottom doors, means for feeding sheaves to said shocking-chamber, and means for automatically raising said rotary member and opening said bottom and rear doors when said shocking-chamber becomes full. 85 90

7. A shocking-machine having a shocking-chamber, a rotary member mounted in said shocking-chamber and dividing the same into a plurality of compartments, means for feeding sheaves to said shocking-chamber, means for operating said rotary member each time one of said compartments becomes 100 full, bottom and rear doors for said shocking-chamber, means for automatically raising said rotary member when said shocking-chamber becomes full, and means for automatically opening said bottom and rear doors 105 during the upward movement of said rotary member.

8. A shocking-machine having a shocking-chamber, bottom and rear doors for said shocking-chamber, a rotary member located in said shocking-chamber, conveying means consisting of a pair of endless belts for conveying sheaves into said shocking-chamber, a rocking member mounted between said endless belts and adapted to be operated by 110 contact with the sheaves, and means controlled by said rocking member for automatically raising said rotary member and opening said doors when said shocking-chamber becomes full. 115 120

9. A shocking-machine having a platform, a ground-wheel, a shocking-chamber mounted on said platform and having bottom doors, springs exerting their tension to open said bottom doors, flexible elements connected with said bottom doors, an auxiliary shaft having a drum to receive said flexible elements, a weighted rear door having a flexible element, a second drum on said auxiliary shaft to receive said last-mentioned 125 130

flexible element, a rotary member mounted in said shocking-chamber, a vertically-movable yoke connected with said rotary member, an eccentric for raising said yoke, a pair of endless belts for feeding sheaves to said shocking-chamber, a rocking member mounted between said endless belts, means operated by said rocking member for automatically causing a step-by-step rotation of said rotary member, means for operating said eccentric to raise said yoke and rotary

member when said shocking-chamber is full, and means operated by the upward movement of said yoke for rotating said auxiliary shaft to open said bottom and rear doors. 15

In testimony that I claim the foregoing as my own I have hereto affixed my signature in the presence of two witnesses.

CHARLEY W. ANDERSON.
